US0D1073220S

(12) **United States Design Patent** (10) **Patent No.:** **US D1,073,220 S**
(45) **Date of Patent:** **** Apr. 29, 2025**

(54) **FLUID CONTAINER RINSER**

(71) Applicant: **Starbucks Corporation**, Seattle, WA (US)

(72) Inventors: **Claudia Ying Yu Lee**, Hong Kong (HK); **Hau Yan Lai**, Hong Kong (HK); **Ming Yim Wu**, Hong Kong (HK); **Wing Chi Tam**, Hong Kong (HK); **Sheryl Wing Yan Tu**, Hong Kong (HK)

(73) Assignee: **Starbucks Corporation**, Seattle, WA (US)

(**) Term: **15 Years**

(21) Appl. No.: **29/869,192**

(22) Filed: **Dec. 23, 2022**

(51) LOC (15) Cl. **15-05**

(52) U.S. Cl.

USPC **D32/2**

(58) **Field of Classification Search**

(57) **CLAIM**

The ornamental design for a fluid container rinser, as shown and described herein.

DESCRIPTION

FIG. 1 is a perspective top view of a new design for a fluid container rinser, according to one embodiment of our new design;

FIG. 2 is a perspective bottom view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is a perspective top view of a new design for a fluid container rinser, according to a second embodiment of our new design;

FIG. 10 is a perspective bottom view thereof;

FIG. 11 is a front view thereof;

FIG. 12 is a back view thereof;

FIG. 13 is a left side view thereof;

FIG. 14 is a right side view thereof;

FIG. 15 is a top view thereof; and,

FIG. 16 is a bottom view thereof.

Broken lines are used to illustrate features of the fluid container rinser that form no part of the claimed design.

1 Claim, 12 Drawing Sheets
